UNITED STATES PATENT OFFICE.

EDOUARD LOUIS TISSOT, OF BASEL, SWITZERLAND.

DISPLAY APPARATUS.

Application filed December 1, 1926, Serial No. 152,034, and in Switzerland November 19, 1926.

This invention relates to an automatic inscription and indication changing apparatus, which can be used for example for advertising purposes. This apparatus is 5 characterized by a large number of individually movable panes arranged in a display surface so as to be movable in relation thereto, these panes being so controlled selectively from a pattern gear operating 10 similar to a jacquard gear, that the one or other of the panes are moved relatively to the display surface according to the pattern, thus producing an inscription or illustration standing out in relation to its surroundings.

15 The accompanying drawing illustrates an embodiment of the invention. Figure 1 is a side view partly in section, Figure 2 is a front view and Figures 3 to 5 show details.

The display surface for the inscriptions 20 and indications consists of similar individually movable panes arranged in a frame *a* side by side and above and below one another, which when set stand up sharply against a background and which each consist of an 25 indicating plate, which can be swung about a horizontal axis *c* in the frame *a* from a vertical position (the indicating position) to a horizontal position (out of use position).

The form of these panes *b* is so designed 30 that individually they do not form a complete inscription or illustration, but only by the combination of a sufficient number of panes *b* does an inscription or illustration which can be varied in accordance with the 35 combination of panes and their number appear on the display surface.

Each pane *b* has an ear *d* (Figures 3 and 4) into which a rod *e* is jointed, which is connected at its other end with a lever *f*. From 40 the lever *f* turnable about the point *g* hangs a tappet rod *h*. Beneath these tappet rods *h* are matrices *i* arranged in groups, which are secured around a drum *j*, which for example in the present case has six sides, and 45 carries on each side one of the matrix groups. The matrices secured to the sides of the drum are each formed with two parallel rows of differently formed and arranged notches *i'*, or with only one row of notches 50 on one edge, or with no notches at all, according to whether all or only some of the tappet rods are to be left unoperated, or all are to be raised, similarly as this is effected in jacquard mechanism, to which 55 the present patterning method corresponds. One of these matrices *i* is shown in detail

in Figure 5. The drum *j* is rotatably supported. Its shaft *j'* carries a six slotted Geneva wheel *t*, which can be rotated intermittently by the tooth *k'* of a one-tooth 60 wheel *k*. The latter is rotated from a toothed wheel *l'* coupled to it and which is driven by a toothed wheel *l*. This wheel *l* is secured upon a shaft *r* which can be driven by any desired motive source. The shaft *r* 65 which carries the toothed wheel *l'* is provided with a cam disc *s* furnished with two diametrically opposite cams.

The hub of the Geneva wheel *t* is provided with a groove *t'* in which engages the forked 70 end of a lever *m*. This lever *m* has a throw over ring *m'* which carries two pins *m''* which engage in the groove of a grooved shifting cam *n*. A groove *o* in the hub of the cam disc *s*, in which the lower end of the lever *m* 75 rests saddle fashion, forms the fulcrum of the forked lever *m*.

The cam disc *s* co-operates with a spring controlled two armed lever *p*, which is connected by a rod and lever gear *p'* with two 80 slidably guided suspended bearings *q* for the drum shaft *j'*, so that the drum *j* can be raised and lowered vertically which it will be understood must be effected when the tooth *k'* is out of engagement with the Geneva wheel *t*. The operating members are suitably arranged with this in view, the rotation of the drum *j* only taking place when it is in the lowest position, while after rotation the cam disc *s* permits the spring controlled lever gear *p'* to act on the drum so as to raise it with yielding elastic pressure 85 against the tappet rods *h* and by means of the notches *i'* in the uppermost matrices *i* to produce the desired selection of tappet rods *h*, so that only the rods *h* raised by the uppermost matrices effect a swinging down or disappearance of the corresponding panes *b* 90 from the display surface, while the other panes remain unaffected and in their combination form the display matter standing up against the background, in correspondence with the selective design of these matrices.

If any inscription is required on the display surface, say the letter *E* for the formation of which the panes shown hatched in Figure 2 are suitable for example, then when the drum is raised the uppermost matrices *i'', i''', i''''', i'''''* of the drum so act with 100 their left hand pattern range, that all the panes *b* which do not take part in the for-

mation of the letter E, that is the panes extending round the outline thereof, are caused to disappear into horizontal position by the action of the corresponding tappet 5 rods, so that only panes directly forming the letter E remain standing in indicating position. This raising of the drum takes place when one cam of the disc *s* runs off the lever *p*. On further rotation of the shaft *r* 10 the second cam of the disc *s* engages the lever *p* and thus lowers the drum *j*. The previously raised tappet rods *h* descend by their own weight and while the drum is still held down by this cam, the grooved shifting 15 cam *n* comes into action in order to move the drum *j* axially through the lever *m* and to set the right hand pattern range of the uppermost matrices of the drum beneath the tappet rods *h*. Since this pattern range has 20 a different form and arrangement from the left hand range, as soon as said cam of the disc *s* leaves the lever *p* and the drum *j* is again raised, an alteration in the selection of tappet rods is effected which with suitable 25 patterning will produce a different indication from the letter E. The first cam of the disc *s* again comes into action to lower the drum *j* and efface the matter on the display surface. While the drum *j* is thus held 30 down, the groove shifting cam *n* also acts to return the drum *j* axially, while the Geneva wheel mechanism hitherto out of action, rotates the drum in known manner through 60° by action of the single tooth *k*¹ which 35 has in the meantime arrived into position for operation, so that the matrices on the next side of the drum come into the working position, and the selection of the tappet rods *h* and panes *b* takes place again as described 40 above, the indications shown being of course different.

It will be seen that by means of the drum *j* a very large selection among the panes *b* can be achieved and that after selection the picture or indication produced remains in 45 the display position unchanged for a time, to be shown again unchanged, or to be changed according to whether the matrices on the drum have the same or different patternings. By changing the matrices on the 50 drum while the apparatus is brought to rest which can be effected by uncoupling the pictures or indications can be changed without limit.

What I claim is:

An automatic inscription and indication changing apparatus, comprising a large number of individually movable indicating elements within a display surface, an intermittently rotatable pattern drum, said drum carrying a plurality of groups of pattern matrices having each a plurality of parallel pattern ranges, movable selectors between said pattern drum and said indicating elements, means to intermittently rotate the pattern drum for positioning one or other of its pattern matrix groups, means to axially shift said pattern drum so as to adjust the matrices of the positioned group thereof by one or other of their pattern ranges into 70 operative position with respect to the selectors, and control means to bring said pattern drum and selectors into cooperative relation with one another so as to cause in accordance with the operative design of the 75 pattern drum a selection among said indicating elements for indicating purposes.

In witness whereof I have hereunto signed my name this 19th day of November, 1926.

EDOUARD LOUIS TISSOT.
